UNITED STATES PATENT OFFICE

2,547,343

HANDGRIP FOR CARRYING PARCELS,
PACKAGES, BUNDLES, ETC.

Edward K. O'Loughlin, Brookline, Mass.

Application March 5, 1949, Serial No. 79,816

3 Claims. (Cl. 224—57)

1

This invention relates to improvements in hand grips for carrying an article, such as a parcel, bundle, or the like, having a supporting cord or cords extending longitudinally thereof, with transverse sections extending around the same midway of its length and knotted together at the ends thereof.

The object of the invention is to provide an improved hand grip of thin rigid material adapted to be grasped by the hand of the user and having means adjacent its end detachably to engage the supporting cord or cords in such manner as to prevent relative slipping movement therebetween.

A further object of the invention is to provide a hand grip of the character described which can be economically manufactured and preferably of such construction that any number thereof may be superimposed or nested for storage and transportation.

A further object of the invention is to provide a hand grip for supporting an article having a binding cord of the character described which can be readily and conveniently applied to the binding cord.

Another object of the invention is to provide a hand grip of the character described which will permit the thumb of the user to be pressed on the knot connecting the ends of the binding cord more effectively to prevent slipping or release of the knot which connects the ends of the binding cord or cords.

Preferred embodiments of the invention are illustrated in the accompanying drawings, in which,

Fig. 1 shows a rectangular bound parcel with an arcuate hand grip engaging the binding thereof and supported by the hand of the user, which is illustrated in broken lines;

Fig. 2 is a detail plan view of the hand grip illustrated in Fig. 1;

Fig. 3 is a vertical sectional view on line 3—3 Fig. 2;

Fig. 4 is a side elevation similar to Fig. 1 showing a different manner in which the hand grip may be applied to the binding cord;

Fig. 5 is a detail side elevation of a hand grip and binding cord as illustrated in Fig. 4; and

Fig. 6 is a perspective view of a modified form of invention as applied to parallel supporting cords of the usual type of shopping bag.

The invention broadly comprises a hand grip for carrying an article having a supporting cord or cords extending around the article lengthwise thereof and transversely around the article midway of its length with the ends of the cord knotted

2

together in which the hand grip which extends longitudinally of the article is provided with parallel edges and ends with apertures adjacent the ends thereof and slots of the bayonet type having slot sections extending inwardly from the ends in alignment with each other and offset from the apertures, with lateral sections leading to the respective apertures.

In the simplified form, as illustrated in Fig. 6, 10 the hand grip comprises a thin rectangular flat plate 1 of longitudinally stiff material having parallel edges 2 and 3 with apertures 4 and 5 centrally of the width thereof and having slot sections 6 and 7 extending inwardly in alignment and offset from the apertures 4 and 5, and slot sections 8 and 9 preferably at right angles thereto communicating with the apertures 4 and 5. Preferably the edges of the plate are provided centrally of its length with shallow recesses 10 and 11 extending a short distance inwardly. In the operation of a hand grip of this character which is shown as supporting cords 12 and 13 attached respectively to the upper end walls 14 and 15 of a shopping bag, the plate is moved edge-wise under the cords 12 and 13 to cause the cords to drop into the slot sections 6 and 7, then to slide into the branch sections 8 and 9 and then into the respective apertures 4 and 5, and the hand, when introduced beneath the hand grip, enables the bag to be readily carried by the user.

The intermediate notches 10 and 11 may be employed to receive the transverse members of a binding which encircles the central portion of the article, as will hereinafter more fully appear.

35 In the preferred embodiment of the invention, which is illustrated in Figs. 1 to 5 inclusive, the hand grip comprises an arcuate, preferably semi-cylindrical, plate 16 of suitable thin rigid material having centrally of its width apertures 17 and 18 in suitable proximity to the ends thereof, with bayonet slots 19 and 20, similar to those shown in Fig. 6, extending inwardly from the respective ends and communicating with the apertures 17 and 18. In this construction similar 40 recesses 21 and 22 are shown extending inwardly from the edges of the sheet or body midway of the length thereof to receive transverse sections of the binding cord which transversely surrounds the article.

45 In the operation of the construction shown in Fig. 1 the plate 16 of the hand grip is moved edge-wise with a rolling motion beneath the longitudinal section 23 of the binding cord causing the longitudinal binding cord section 23 first to ride 50 on to the plate and drop into the aligned sections 55

of the slots 19 and 20 and then to slide through the angular sections into the apertures 17 and 18. When there is also a transverse binding cord, the transverse end sections 24 and 25 are introduced into the apertures 21 and 22 with the knot 26 connecting said ends resting upon the plate 16 midway of the length of the hand grip. The hand of the user, which is illustrated in dotted lines in Fig. 1, may then be inserted beneath the hand grip and the thumb of the operator swung from the position shown into engagement with the knot 26 to prevent relative slippage between the hand grip and the binding cord and also to prevent release of the knot 26.

It will be noted that the apertures into which the binding cord moves when the hand grip is in place are substantially larger in diameter than the width of the bayonet slots. Consequently, any slight tension on the binding cord and particularly the tension applied when the article is lifted by the hand grip locks the binding cord in these apertures and prevents its slipping back into the bayonet slots. Also this relation of the parts prevents the grip and the cord from being disengaged when the package is put down and the hand released from the hand grip. Furthermore, when the bayonet slot is of a width so related to the diameter and character of the binding cord that the binding cord can just pass through the slot or has to be forced therethrough the cord will expand or revert to its normal size because of the larger diameter of the apertures and this further prevents disengagement of the grip and cord.

As illustrated in Figs. 4 and 5 the longitudinal portion of the binding cord may be similarly introduced into the apertures in the hand grip, but with the knot located below and in engagement with the under face of the hand grip instead of within the hand grip, as shown in Fig. 1, in which case the recesses 21 and 22 may be omitted as unnecessary.

The hand grip embodying the invention may be formed in any desired manner as by casting, stamping, or die shaping, or otherwise, within the spirit and scope of the invention.

By reason of the construction above described hand grips may be conveniently and economically manufactured and which can be superimposed

upon each other or nested together into packages which can be conveniently stored or transported.

It will be understood that the particular embodiment of the invention as shown and described herein is of an illustrative character and not restrictive and that various modifications may be made within the spirit and scope of the following claims.

Having thus described the invention, what is claimed as new, and desired to be secured by Letters Patent, is:

1. A hand grip, for carrying an article having a binding cord extending thereover, comprising a plate of thin rigid material having an aperture at each end and spaced therefrom centrally of its width and having a bayonet slot at each end, with one section of each slot opening through an end of the plate and with said sections extending inward in alinement with each other and offset from the apertures and with the other section of each slot extending angularly from the first section into the adjacent aperture, the said grip acting, when moved edgewise under the cord, to cause the cord successively to ride on to the plate, to drop into the first sections of the two slots, and then to slide through the angular sections into the apertures.

2. A hand grip as defined in claim 1, in which the plate is of substantially semi-cylindrical shape thus with its side edges widely spaced enabling it to be moved edgewise on to the cord readily with a rolling motion.

3. A hand grip as defined in claim 1, in which the said apertures are of larger diameter than the width of the bayonet slots thus to assist in preventing disengagement of the grip and binding cord when the grip is in holding position thereon.

EDWARD K. O'LOUGHLIN.
